UNITED STATES PATENT OFFICE.

JAMES L. BALDWIN, OF CHICAGO, ILLINOIS.

STORE-SERVICE APPARATUS.

1,419,200.

Specification of Letters Patent. Patented June 13, 1922.

Application filed November 12, 1920. Serial No. 423,594.

To all whom it may concern:

Be it known that I, JAMES L. BALDWIN, a citizen of the United States of America, residing at Chicago, in the county of Cook and

5 State of Illinois, have invented a new and useful Store-Service Apparatus, of which the following is a specification.

My invention relates to store service apparatus in which a track wire is provided on 10 which a basket car travels and means for catching and throwing the car from the station in combination with means for elevating and lowering the basket to and from the track, and the objects of my improvements 15 are, first, to eliminate the customary springs on the elevator; second, to have the track wire serve as the positioning element for the elevator; third, to have the elevator pull cord pulleys mounted on a pivoted bracket 20 to which the elevator stop rod is secured; fourth, to provide a safety guide for the thrower cord; fifth, to make a simple, cheap and durable apparatus, and other features to become apparent from the description to 25 follow.

In store service apparatus of the class to which my invention pertains it is very desirable to have the least number of parts possible and yet attain efficient service; to guard 30 against damage should any of the wearing parts break; to make the apparatus easy to operate and fool-proof; to so position the elevator with respect to the incoming car that long and continuous use, which neces- 35 sarily wears the parts, will not materially vary the position of the elevator with respect to the incoming car; and to eliminate as many springs as possible, and I attain these several objects by the use of my invention.

40 To describe my invention so that others versed in the art to which it pertains can make and use the same I have illustrated it on the accompanying two sheets of drawings in which:—

45 Figure 1, is a side elevation of a store service apparatus embodying my invention; Figure 2, is an enlarged plan view of the same partly broken away and Figure 3, is an end elevation of the same showing the elevator pull cords and their connections.

Similar reference characters refer to similar parts throughout the several views.

The apparatus is supported on the lower 55 end of a vertically disposed pipe 4 secured to the ceiling or other suitable part of the

store. The track wire 5 extends to the right of the support 4 as viewed in the illustration and two guy wires 6 are provided to hold the track wire 5 taut.

The track wire 5 is secured to a small clip 60 7 which is secured by a horizontal pivot 8 to the bracket 9 which is mounted on the lower end of the pipe 4 in such manner that it can swing about a vertical axis which preferably coincides with the axis of the pipe 4. Set 65 screws 10 are provided to rigidly secure the bracket 9 in place after the same has been properly positioned. The guy wires 6 are secured to a sleeve 11 which is loosely mounted on the pipe 4, but can be secured in place 70 by means of a set screw 12 or otherwise.

Extending parallel to the track wire 5, and spaced a short distance below the same in the same vertical plane therewith is arranged a flat track, 13 on which the thrower 75 14 is mounted to slide. The track 13 is secured to the bracket 9 by means of a horizontal pivot 15 and to the track wire 5 some distance from the bracket 9 by means of the pulley bracket 16, which has mounted thereon the pulley 17. One end of the thrower cord 18 is secured to the thrower 14 and from thence passes around the pulley 17, thence over the pulley 19, mounted on bracket 9, thence down around the floating 85 pulley 20 mounted in the block 21, thence up over the pulley 22, mounted on bracket 9, and thence down to the pulley block 21, where its other end is secured. The thrower pull cord 23 is secured to the pulley block 21 90 and depends from the same having a handle 24 secured to its lower end.

It will be noted that, since the track wire 5 is free to swing vertically about the pivot 8 and horizontally about the pipe 4 as a pivot, 95 the thrower track 13 will always be held parallel to the track wire 5, thus insuring that the thrower 14 will always travel in the proper path with relation to the carrier which travels on the track wire 5.

When the car, not shown, which travels on the track wire 5 enters the station, i. e., the apparatus shown in the drawing, the catch provided on the car will enter and be caught by the catcher hook 25, which is provided 105 with a rearwardly extending rod 26 which passes freely through a hole provided in bracket 9 at 27. A buffer spring 28 is interposed between frame 9 and the hook 25 and a recoil buffer spring 29 is interposed be- 110

tween the frame 9 and a suitable stop provided on the extremity of the rod 26. Extending upward from the hook 25 is an integral arm 30 which is provided at its upper 5 end with a fork 31 to straddle the track wire 5, and a suitable pin 32 is secured in the free ends of the fork 31 above the track wire 5 so that the hook 25 is carried by the track wire 5, which arrangement at all times properly 10 positions the hook 25 to register with the incoming car not shown. This is true even though the track wire 5 is moved to either side or up and down.

The elevator, which is provided to lower 15 and elevate the basket which is detachably connected to the car which travels on the track wire 5, comprises the usual stirrup 33 whose operation and connection with the basket and car, not shown, is fully shown and described in a former patent issued to me December 28, 1915, No. 1,165,565; the basket and car forming no part of this invention. The stirrup 33 is raised and lowered by being secured to two cords, or more properly speaking, to the two ends of a single piece of cord 34. The two ends of the cord 34 are secured to the stirrup 33 at 35 on either side of the track wire 5, from whence they pass upward over pulleys 36 mounted on the free ends of the U shaped frame 37, thence to the left and 20 up over pulleys 38 mounted on bracket 39 and thence downward to the counter weight 40 wherein the cord is looped around through a suitable cavity formed therefore in said counter weight 40. Thus it is clearly seen if the counter weight 40 is pulled down the stirrup 33 will be lifted and when the counter weight 40 is raised the stirrup 33 will descend. The counter weight 40 is made sufficiently 25 heavy to always hold the stirrup 33 in an elevated position adjacent the free ends of the frame 37, but sufficiently light to be raised, when the basket, not shown, is resting on the stirrup 33. The U shaped frame 37 is connected to the bracket 9 to swing about the horizontal pivot 41. A short distance from the bracket 9, the U shaped frame 37 is provided with an integral cross bar 42, and secured to this cross bar 42 is an upright 43 which has a right angle hook at its upper end 30 extending over the track wire 5 so that the position of the free ends of the frame 37, vertically, is determined by the track wire 5. The lateral position, or the position horizontally 35 of the frame 37 is determined by the bracket 9, and corresponds to the position of the track wire 5. Thus it will be seen that the position of the free ends of frame 37, both horizontally and vertically, corresponds to the position of the track wire 5, and since the stirrup 33 depends from the free ends of the frame 37, said stirrup 33 is held in proper 40 registering position with the incoming car, not shown, by the track wire 5.

65 Thus it is seen that the thrower 14, the

catcher hook 25 and the stirrup 33 are each held in its proper operating position by the track wire 5.

The elevator pull cord 44 is secured to the counter weight 40 and has a handle 45 secured to its lower end. The counter weight 40 is made in the form of a curved frame so it can conveniently be placed or caught under the inverted hook 46 formed near the lower end of the rod 47 which has its upper 70 end secured in the bracket 39, pivotally mounted on the free end of the arm 48 secured to the pipe 4. The bracket 39 is made to swing freely on the horizontal pivot 49 so that said bracket 39 will always adjust itself 80 in line with the pull on the pull cord 44; and the stop hook rod 47 being rigidly secured to the bracket 39, it will also be held in line with the pull on said pull cord 44, so that the counter weight 40 can easily be placed under 85 the hook 46.

In operation the normal position of the apparatus is with the basket, not shown, resting on the stirrup 33 and the counter weight 40 caught under hook 46. To lower 90 the basket to within reach of the operator, the counter weight, 40 is pulled out from under hook 46 and permitted to move up until it comes to a stop against the bracket 39. To elevate the basket and couple it onto 95 the car, not shown, resting on the track wire 5, the elevator pull cord 44 is pulled down until it comes to a stop. The pulling down on the pull cord 44 will lift the stirrup 33 with the basket until the stirrup 100 contacts with the free ends of the U shaped frame 37, when a further pull down on the pull cord 44 will also lift the free ends of frame 37 about its pivot 41 until the basket contacts with the car and is locked 105 thereto; whereupon the pull on pull cord 44 is released and the weight of the free ends of frame 37 being greater than the counter weight 40, the free ends of frame 37 110 will swing down about their pivot 41 until the bent end of the upright 43 contacts with the track wire 5.

To throw the car with the basket attached thereto out from the station the pull cord 23 is pulled down until the 115 thrower 14 comes to a stop against the bracket 16. When the car with the basket attached thereto is returned to the station the thrower 14 is carried back by the car and the catch on the car locks itself to the 120 catcher hook 25 with the basket bail resting above and free from the stirrup 33. To return the basket to its normal position the pull cord 44 is pulled down until it comes to a stop with the free ends of the frame 125 37 raised sufficiently to have the stirrup 33 lift the basket and disconnect it from the car; whereupon the pull cord 44 is permitted to move upward until the counter weight 40 is caught under the stop hook 46. 130

The lower extremity of the rod 47 is provided with an eye 50 through which the thrower pull cord 23 passes, which prevents the pulley block 21 from falling and causing 5 damage should the thrower cord 18 become severed.

It will be understood that the size, shape, form and arrangement of the parts may be changed without in the least departing from 10 the scope of my invention.

Having thus fully described my invention what I claim as new and desire to secure by Letters Patent of the United States is:—

1. In a device of the class described, a 15 support, a track wire for a car to travel on, a thrower for the car, a thrower rail supported at one end by the track wire, a catch for the car supported at one end by the track wire, and an elevator supporting 20 arm supported by the track wire.

2. In a device of the class described, a support, a bracket mounted on the support arranged to swing about a vertical axis, a 25 track wire attached to said bracket, a thrower rail having one end supported by said bracket and the other end supported by the track wire, a car catch supported at one end by said bracket and at the other end by the track wire, and an ele-

vator supporting arm pivotally connected 30 to said bracket and having means to engage the track wire to position the free end of said elevator supporting arm.

3. In a device of the class described, a support, a track wire secured to said support and extending therefrom, and an elevator supporting arm pivotally connected to said support and provided with a stop 35 to engage the track wire to position the free end of the same.

4. In a device of the class described, a support, a track wire, an elevator, a pull cord for operating the elevator, a pulley over which said pull cord travels, a pulley bracket mounted on the support to swing 45 about a horizontal axis in which the pulley is mounted, a stop rod for the elevator cord rigidly mounted on said bracket to swing therewith, and a means on the elevator cord to engage the said stop rod.

In testimony whereof I have signed my name to this specification in presence of a subscribing witness this 30th day of October, 1920, at Chicago, Illinois.

JAMES L. BALDWIN.
